UNITED STATES PATENT OFFICE.

GEORGIA W. WHEATON, OF APPLETON, WISCONSIN.

METHOD OF FINISHING PAPER.

1,407,611.

Specification of Letters Patent. Patented Feb. 21, 1922.

Application filed May 22, 1920. Serial No. 383,481.

To all whom it may concern:

Be it known that I, GEORGIA W. WHEATON, a citizen of the United States, and resident of Appleton, in the county of Outagamie and State of Wisconsin, have invented new and useful Improvements in Methods of Finishing Paper, of which the following is a description, reference being had to the accompanying drawings, which are a part of this specification.

The present invention relates to a certain new and useful process or method of producing a finish on paper more especially correspondence paper.

One object of the present invention is to provide a method of finishing paper which will produce a paper of extremely neat appearance and having a design therein and which will also serve to provide a surface on the paper that will give the cheaper grades of paper the appearance of hand made paper.

In finishing the cheaper wood paper, a sizing is employed which presents a surface upon which ink does not take very readily, and it is another object of my invention to provide a method of finishing paper which will so surface the paper as to give the same the appearance of a better grade paper and at the same time adapt the same to readily receive ink.

A further object of the present invention is to provide a method of finishing paper which will permit the employment of any number of designs without the necessity of an expensive outlay of dies, etc., thereby permitting the production of the finished paper at a comparatively low cost, all things considered.

With the above and other objects in view which will appear as the description proceeds, my invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawing I have illustrated one complete example of the physical embodiment of my invention constructed according to the best mode I have so far devised for the practical application of the principles thereof, and in which:

Figure 1 is a view of a number of sheets

of paper arranged according to my improved method and subjected to pressure to impress the finish therein; and

Figure 2 is a view of a stack of paper ready to be placed within the pressure means, parts being broken away.

Referring now to Figure 2 of the drawing, 5 designates a base plate preferably of zinc or any similar material upon which is placed a wet or moist cloth 6 which is preferably of linen or part linen; 7 designates one or more sheets of paper to be finished which are placed over the wet cloth 6; 8 designates a cloth of any desired material which has 10 worked therein any desired design, which cloth is placed over the sheet or sheets of paper 7; 9 designates one or more sheets of paper placed over the cloth 8; and 10 designates a wet or moist cloth similar to cloth 15 6 which is placed over the sheet or sheets of paper 9.

With the parts in the relation just described, pressure is applied thereto which will impart the design of cloth 8 to the 20 paper 7 and 9, after which the parts are removed from the pressure means and the sheets of paper permitted to dry. As will be readily apparent any number of alternate layers of wet cloth, paper, designed cloth, 25 etc., may be employed, and in Figure 2 I have illustrated several cloths 8, layers of paper 7, and wet or moist cloths 6.

The pressure means which I employ may be in the form of a hand press as depicted 30 in Figure 1 comprising a base 11 and an overhanging arm 12 connected with the base and provided with a central threaded bearing 13 in which is mounted a screw shaft 14. This screw shaft 14 has a plate or plunger 35 15 mounted on one end thereof and a hand operating wheel 16 mounted on the other end thereof.

When the alternate layers of paper, etc. have been stacked the entire stack is positioned upon the base 11 and the shaft 14 screwed down by a hand wheel 16 to apply 40 pressure thereto, which, by reason of the paper being dampened or moistened by the cloths 6 or 10 will cause the design worked in 45 the cloths 8 to be impressed in the paper 7. The stack is preferably left in the press for a period of time and when removed, the paper is separated and permitted to dry.

It has been found from experience that the 50 ordinary wood pulp paper which ordinarily does not take ink very readily will be given

the appearance of a higher grade hand made paper and at the same time take ink the same as the better grades of paper when treated as hereinbefore described.

5 It will be readily seen that the designed cloth or cloths 8 form what may be termed the die and as ordinary scraps of cloth may be employed for this purpose it is possible to obtain a large variety of designs at a minimum expense.

10 What I claim as my invention is:

The herein described method of providing a finish on paper which consists in placing a plurality of sheets of paper in superposed

relation, inserting substantially midway of 15 the stack thus formed between certain of the sheets of paper a cloth having the desired design, placing on the top and bottom of the stack, respectively, sheets of moistened material and then applying pressure to the 20 stack, whereby the moisture is transferred from the last mentioned sheets of material to the paper, and the latter conditioned to receive the impressions of the design in the cloth.

25

In testimony whereof, I affix my signature.

GEORGIA W. WHEATON.
